KNITTING METHOD AND MACHINE

Paul W. Eristow, Laconia, N. H., assignor to Scott & Williams, Incorporated, Laconia, N. H., a corporation of Massachusetts

Application October 12, 1944, Serial No. 558,337

19 Claims. (Cl. 66—14)

1

This invention relates to knitting machines of the type having superposed needle cylinders as shown, for example, in the patent to Bentley, 1,713,736, dated May 21, 1929.

In machines of this type, the needles are under the control of sliders and are transferable to and from each needle cylinder to permit the knitting of a continuous fabric such as tubular fabric comprising courses some of the stitches of which are knitted with needles operating in one cylinder while other stitches are knitted by needles operating in the other cylinder. By shifting the needles from one cylinder to the other reverse concatenations of loops are effected to produce, when the shifts are frequent and elaborate patterns are produced, the fabrics which are commonly referred to as links-and-links fabrics. Such fabrics may have quite elaborate designs, such as diamonds or blocks, formed therein and may range to simpler patterns involving fairly continuous ribs, various patterns being the result merely of suitable control of the needle transfers.

The broad object of the present invention is the provision of a knitting machine in which elaborate handling of the needles is made possible with particular insurance that no needle will ever be free of control in both cylinders, i. e., will not be released by both the sliders which are available for its control.

A further object of the invention is the provision of a machine of the type indicated in which tuck and float stitches may be produced in the links-and-links fabric.

Still another object of the invention is to provide a knitting machine of the type indicated in which stockings may be produced, provision being made for reciprocatory knitting of heels and toes with the incidental narrowing and widening operations.

These and other objects of the invention, particularly relating to details of construction, will become apparent from the following description read in conjunction with the accompanying drawings, in which:

Figure 1 is a development of the cams for acting upon sliders, jacks and verges, various associated parts also being illustrated, Figure 1 encompassing these elements throughout one phase of the mechanism;

Figure 2 is a section taken on the plane the trace of which is indicated at 2—2 in Figure 1;

Figure 3 is a perspective view showing certain jack selecting elements;

2

Figure 4 is a section taken on the plane indicated at 4—4 in Figure 3; and

Figure 5 is a development, similar to Figure 1, but showing cams and associated parts particularly involved in a hosiery machine.

The machine to which the present invention is applied may have any number of feeds ranging from a single feed in the simplest case, for example in a hosiery machine, through two feeds which also may constitute a hosiery machine, up to a machine having quite a large number of feeds of the so-called body-knitting type. In the following description, reference will first be made to a modification of the invention particularly adapted to a body machine in which no provision need be made for reciprocatory knitting, narrowing, or widening. In such a body machine, it may be assumed that there is present an even number of feeds grouped in pairs, a pair being herein described as involving a phase of operation. However, an underwear machine may have any desired number of feeds, from one upwards, between transfers. In this case two are shown, by way of example only. If only two feeds are involved, the phase would extend through 360 degrees and the end of a phase would then coincide with the beginning of the same phase. In the case of two phases, each would comprise 180 degrees and they would be arranged in succession so that the end of one would coincide with the beginning of the other. Obviously, such sequential arrangement can be carried on to a quite large number of phases as would be present in a large body machine. It will be evident that a description of one phase will suffice to cover any number of such duplicate phases.

Figure 1 shows in diagrammatic fashion the cams for control of the sliding elements, i. e., sliders, jacks and verges, for a single phase. Each phase comprises two feeds, the first involving a stitch cam 2 arranged to control needles to take yarn from a feeding station indicated at 4 at which one or more yarn feeding fingers may be located, and the other involving a stitch cam 6 arranged for the control of needles to take yarn at a second feeding station indicated at 8 and at which similarly a number of yarn fingers may be provided. The stitch cams 2 and 6 may be axially adjustable for the control of length of stitches drawn thereat.

Beyond the stitch cam 2 there is located a cam 10 serving to cause clearing of latches by loops which are drawn under the action of the stitch cam 2. This cam 10 is radially movable so that when withdrawn needles may ride at a tuck level.

To provide clearing of latches at the second feed there is provided a cam 12 which, alternatively with a control hereafter described, will effect rise of needles in the lower cylinder to a latch clearing height. A cam 13 located immediately beyond cam 12 cooperates with the alternative latch clearing means. Cam 12 is adapted to be radially withdrawn to permit needles to pass at a low level.

Cams 14 and 16, both of which are radially movable, are adapted to effect, when in inner position, rise of needles for purposes hereinafter described. A cam 18 is provided to effect transfer of needles from the lower to the upper cylinder when the needles are partially raised by selective control means. A cam 20 serves to divide two raceways and serves to raise sliders in the lower cylinder which do not carry needles. A cam 24 serves to lower sliders to insure engagement with stitch cam 6 even though, by virtue of adjustment, the stitch cam occupies a position lower than that shown. A similar cam 22 effects the same function in conjunction with the stitch cam 2.

To guard against overrun of the lower sliders as they travel down the stitch cams 2 and 6, there are provided cams 26 and 28 which are vertically adjustable, respectively, along with the stitch cams 2 and 6. These cams also have rises as indicated to insure that the lower sliders properly engage the cams 14 and 12, respectively. Cams 30 and 32 are guard cams which segregate sliders controlling needles 73 through knitting waves from sliders which do not carry needles. Cams 34 and 36 serve to lower sliders in the lower cylinder which do not carry needles to avoid interference with the formation of stitches by needles in the upper cylinder which pass through knitting waves adjacent the positions of these cams.

The cams associated with the upper cylinder include the stitch cams 38 and 40 associated, respectively, with the first and second feeding stations. Cams 42 and 44 associated, respectively, with cams 46 and 48 serve to lower upper sliders to cause needles carried by them to clear their loops. Cams 50 and 52 are arranged to raise upper sliders to present them for proper engagement by the stitch cams 38 and 40, these latter being axially adjustable for the purpose of controlling the lengths of loops knitted by needles in the upper cylinder. Cams 54 and 56 operate alternatively with the cams 42 and 44, cam 54 being joined by a toggle connection with cam 42 and cam 56 being joined by a similar toggle connection with the cam 44. By this arrangement only one of cams 42 and 54 is in operation at the same time, while the same is true of the pair of cams 44 and 56.

Guard cams 58 and 60 are connected to the same blocks as stitch cams 38 and 40 so as to be axially adjustable therewith. They prevent overrun of the needles when they are moved for stitch drawing and also serve by their rises to insure proper engagement of the upper sliders with the cams 42 and 44 following a stitch drawing operation despite extreme adjustment of cams 38 and 40 to draw extra long stitches.

A cam 62 serves to lower upper sliders to effect transfer of needles from the upper cylinder to the lower cylinder while cam 64 serves to restore the upper sliders to a normal level after the transfer of needles therefrom, at which normal level they may again receive needles transferred from the lower cylinder.

The lower and upper sliders which permanently remain in their respective cylinders are indicated diagrammatically at the right of Figure 1. The lower sliders 66 are provided with butts 68 and 70 which, together, by cooperation of the cams, serve to control the movements of the lower sliders. The lower sliders are provided with hooks 72 engageable in conventional fashion with the lower hooks of the double hook needles 73 to serve to control their movements.

The upper sliders 74 are similarly provided with pairs of butts 76 and 78 which, by cooperation with the cams related to the upper cylinder, serve for their control. These upper sliders are provided with hooks 80 engageable with the upper hooks of the needles to actuate them when the lower hooks are operating to handle the yarn.

A cam 82 in the needle transfer region operates in conventional fashion to tilt the sliders to disengage their hooks from the respective needles, as indicated in Figure 2. The action is a conventional one such as described in Houseman Patent No. 2,252,769.

Below the lower sliders are located jacks 116 which are acted upon by a series of controlling cams which will now be described.

These jacks 116 are provided with upper butts 118, saw-tooth butts 119, and lower butts 120 which are provided with undercuts indicated at 122 adapted to be engaged by the sharpened edges of suitable cams. Among the cams cooperating with these butts are 84, 86, and 88. In advance of the cam 84 there are selectively inwardly movable cams 90 adapted to be engaged by the saw-tooth butts 119. A similar group of cams 92 is located in advance of cam 86 while a further similar group of cams 94 is located in advance of the cam 88. Adjacent the groups of cams 90, 92, and 94 are cams 96, 98, and 100, respectively, arranged to engage the outer surfaces of the butts 120 for the purpose of moving these butts inwardly to cause them to avoid engagement with the cams 84, 86, and 88. Cams 102 and 104 are provided with sharpened edges and serve to engage the undercuts 122 of lower sliders which have been pressed inwardly to effect outward movement of the lower ends of these jacks to present them for action of the next selective cams upon their saw-tooth butts, and also to present their butts for possible engagement by the respective cams 98 and 100. Cams 106 and 108 are provided for action upon the upper butts 118 of jacks which are raised by cams 84 and 86. Cam 112 defines a raceway through which butts 118 ride when jacks are raised by the cam 88. The cam 112 is provided with a portion 114 designed to engage butts 118 and lower slightly jacks which are not engaged by the cam 88. A cam 110 serves to lower jacks which were raised by cam 88. Cams 124 and 126 are guard cams which carry additional cams 128 and 130 which act upon the butts 118 of jacks which have not been raised respectively by cams 84 and 86 to insure that these jacks remain in the cylinder slots when the gaps in the vicinity of cams 106 and 108 are reached. A cam 132 serves as a guard cam to define the extent to which butts 118 are lowered by the action of cam 114.

Various other cams are provided, as indicated in Figure 1, which need no special mention, being provided either to prevent overrun of sliders in the event their friction in the cylinder slots is insufficient or to insure movements by acting upon the second slider butt in the event the butt which normally should define the slider movement

breaks. The functions of such auxiliary cams will be evident from the drawings.

Additionally certain cams perform the function of holding the sliders and jacks in their slots and prevent tilting when that is to be avoided.

Referring to Figure 2, the upper cylinder is indicated at 99 and the lower cylinder at 101. These cylinders are provided with the usual slots for reception of the sliders, needles and jacks, the slots being defined by walls, preferably of the inserted type. The lower portions of the walls in the upper cylinder are axially slidable to provide verges 103, the lower ends 105 of which serve to hold the yarn between loops when stitches are being drawn by needles in the upper cylinder. These verges are provided with butts 107 adapted to be acted upon by cams as hereafter described. Conventional arcuate sinkers 109 are provided, controlled in the usual fashion by cams, to cooperate with needles in the lower cylinder during stitch formation.

In Figure 1, there are illustrated all of the possible paths which may be taken by the butts of the upper and lower sliders for the production of the several results of which the machine is capable. As will be evident from that figure, the motions of the sliders are, in general, defined in each passage through the illustrated cams by the actions of the cams on both upper and lower butts; i. e., in a single passage, the motion of a slider might be defined first by action upon a lower butt, then by action upon an upper butt, followed by further action upon a lower butt, and so on. In the figure, the parallel paths of both the upper and lower butts are illustrated, and the complete path may be ascertained by considering the successive actions of the various cams on the butts. The passage of sliders from the right-hand to the left-hand side of the figure will, for convenience, and as pointed out above, be referred to as a phase of operation.

As has been indicated, in a two-feed machine this phase of operation may extend through 360 degrees, so that the sliders leaving the left-hand side of the figure may be considered as immediately reappearing at the right-hand side. On the other hand, as is more usual in underwear machines, the complete circumference of the machine may involve a relatively large number of such phases in which the cams may be quite different.

In any event, the lower sliders may enter a phase along two alternative paths, A and B. Similarly, the upper sliders may enter the phase along two alternative paths, J and L. Beyond this entrance, the paths may be variously split up in fashions which will be best understood by reference to particular events occurring in the phase.

First, there may be considered the operations in the lower cylinder giving rise to normal stitch formation at both feeds. If a lower slider carrying a needle enters at A, or if, as will be pointed out, shortly after entry a needle is transferred thereto from the upper cylinder, the slider in knitting will follow the successive paths C, F and A, so as to enter the next phase (or re-enter the same phase in a two-feed machine) on the path A. In this case, the slider is first slightly depressed at 22, depressed fully, so that its needle will seize yarn, by the cam 2, raised slightly by cam 26 and then by the cam 14, if cam 14 is in active position, then further raised either by its jack, as hereafter described, or by the cam 10 if that cam is in active position, depressed slightly

at 24, fully depressed at the second feed by the cam 6 to take yarn, and then raised, following a slight rise at cam 28, either by the cam 12 or by its jack as hereafter described. In the paths F and A, the latches are cleared.

If a tuck stitch is to be produced by failure of a needle to clear its latch before taking yarn at the first feed station 4, the slider may in a previous phase approach the cam 2 along either of the alternate paths A, C or B, D. After being lowered by the stitch cam 2, it will be raised by the cam 14, and then further raised to the path F either by the cam 10 or by action of its jack. This clears the stitch completed at the first feed. It will then be lowered by the cam 6, but under this condition cam 12 is withdrawn so that it leaves the phase along the path B. As will be evident from consideration of the phase, entry into the next similar following phase along the path B cannot lead to a rise to the latch-clearing level at C but rather, the rise will only occur under the action of the cam 16 to the path D in the approach to stitch cam 2. Consequently, yarn is again taken at the first feed of this following phase without clearing of the loop which was taken at the second feed. Tucking will, therefore, occur. As will be apparent hereafter, yarn in this following phase may be taken only at the second feed point, in which case the cam 16 will be withdrawn so that the path E will be the continuation of the path B. Very complicated tucking at successive feeds is possible, but this need not be described in the present analysis.

A third alternative involves production of a tuck stitch by failure of a needle to clear its latch before taking yarn at the second feed point. In this case, as before, entry into the phase may occur either along the path A, C or the path B, D, followed by lowering of the sliders by the stitch cam 2 for the seizure of yarn at the first feed point. The sliders are then raised by the cam 14, but in this case, the cam 10 will be withdrawn and the slider will not be raised by its jack, with the result that it will follow the path G which is insufficiently high to cause latch-clearing. The loop of yarn from the first feed point is, therefore, carried in the hook along with the yarn seized at the second feed point by the action of the stitch cam 6 and is cleared by the subsequent rise of the slider over the cam 12, or by the action of its jack, to the path A.

Multiple tuck stitches may be produced by entry of the slider along the path B, D, and depression by the stitch cam 2 to take yarn at the first feed point followed by path G resulting from withdrawal of the cam 10 and absence of action by the jack. Yarn is then taken at the second feed point under the action of the stitch cam 6. The slider may then rise up cam 12 if this cam is in active position or travel up, by action of its jack, to path A; or, on the other hand, it may remain in path B so that in the next phase, the stitch may be cleared with rise of the needle to the latch-clearing level either at the first or second feed, it being possible to take yarn again at the first feed or to pass this feed without taking yarn under the float conditions hereafter described.

To produce a draw stitch at the first feed, the slider must enter on the path B and then follow the path E, resulting from the withdrawal of the cam 16. If yarn is to be taken at the second feed either for forming a tuck or a normal stitch, the slider then rises over cam 14 to follow the path G or over both cam 14 and then, by the action of cam 10 or by jack action, to the path F.

To produce a draw stitch at the second feed, cam 14 is withdrawn so that after passing the position of the stitch cam 2 the slider will follow the path H. If a stitch in the phase is to be made with the yarn at the first feed, clearing of the latch by the loop of this yarn is then effected by rise of the slider to the path A either by the action of the cam 12 or rise of the jacks.

The above describes in a general way the possible alternative actions of needles controlled by sliders in the lower cylinder in a single phase. It will be evident, however, that the ultimate stitch formation in the fabric may depend, in certain instances, on what has occurred in the preceding and succeeding phases, and, in fact, several instances of that have been heretofore indicated. It is possible, therefore, that quite complicated stitch arrangements may be produced.

One further action of the slider in a phase may take place attending transfer of a needle from a lower slider to the corresponding upper slider. This will be more fully described hereafter, but it will suffice to point out at the present time that in this case the lower slider enters at A either carrying the needle to be transferred or empty, the latter along the shaded portion of the path A. When the unshaded portion of the path is reached, the needle is transferred from the upper cylinder to the slider, but in then following the path O the needle is transferred or retransferred to the upper cylinder, the rise being effected by jack action and the cam 18. Beyond the cam 18 the path O is followed by the empty slider with depressions at 34 and 36 for the purpose of getting the slider out of position to interfere with the needle latch when the needle is raised in the upper cylinder by cams 38 and 40 and the latch is closing upon the seized yarn. If the empty lower slider continued to follow a path at a higher level it would be in the path of swing of the latch and would interfere with yarn seizure.

The upper sliders also have alternative paths for the production of different stitches and for effecting transfer. If knitting at both feeds is to occur, the upper slider, which may or may not carry a needle, will enter along the path L and will be depressed by the cam 62. If, at this time, it carries a needle, the needle will be transferred to the lower slider so that through the shaded portion of the path, the upper slider will not carry a needle. When the position in line with the cam 18 is reached, however, and if the corresponding lower slider is raised over cam 18, the upper slider will thereafter carry a needle and will be raised successively by the cam 50 and the stitch cam 38 at the first feed to take yarn thereat. It will then be advanced by the cams 42 and 46 along the path M to a level serving to clear the latch. Following this, it is again raised by the cams 52 and 40 to take yarn at the second feed and is advanced by the cams 44 and 48 to follow the path N to effect clearing of the latch. Thus stitches are completed at both the feeds and entry into the next phase takes place along the path L.

If knitting is to occur at the first feed and a draw stitch is to be produced at the second, the path is as just described past the stitch cam 38. In this case, however, the cam 42 is withdrawn so that the path K is followed. The cam 44, however, remains in action so that the slider is advanced by the cams 44 and 48 along the path N to effect clearing of the stitch. This clearing may, however, be delayed until a subsequent

phase, by withdrawal of the cam 44 in which case the path J will be followed.

If a draw stitch is to be produced at the first feed and knitting is to occur at the second feed, the slider must enter the phase along the path J, when transfer of its needle to the lower cylinder will not occur and under which condition it will not cause seizure of the yarn at the first feed, being only slightly raised by the stitch cam 10 and then slightly re-advanced by the cam 58 to engage the cam 42 now in action which, together with cam 46, will cause it to follow the path M. It is then raised by cams 52 and 40 to take yarn at the second feed following which it will take the path N, if cam 44 is active, in order to clear the latch or, alternatively, the path J if the cam 44 is withdrawn, with deferring of latch-clearing until the next phase.

Draw stitches will be produced at both feeds if cams 42 and 44 are both withdrawn, in which case the path will be J, K, J.

It may be noted that all of the various paths just described may be followed not only by sliders which carry needles, but by empty sliders to which needles are not transferred at the position of cam 18. Such empty sliders may thus go along with sliders carrying needles in the upper cylinder without having any effect.

The transfer of all needles entering along path L from the upper cylinder to the lower cylinder by cam 62 is a necessary event if patterns of links-and-links type are to be produced, or if changes from one type of rib structure to another are to be made. However, where a considerable length of fabric is to be produced without a change in the rib arrangement, as, for example, a 1x1 rib top or a broad rib leg, it is not necessary to produce transfers of needles in each course. In such case, once the desired needle arrangement is secured, cam 62 may be withdrawn so that the sliders pass it at the level of path L, thereafter going through any of the various waves described above. At the same time, of course, jack selection of the lower sliders for transfer is interrupted, or cam 18 may be withdrawn.

The action of jacks has been so far merely indicated. The jacks perform three different functions: namely, that of effecting selective transfer of needles from lower to upper sliders, that of providing selection as an alternative to the action of cam 10, and that of providing selection as an alternative to the action of the cam 12. The various possible paths of the jacks will now be described.

As in the case of the sliders, the paths taken by the jacks are determined by the actions of cams upon both upper butts 118 and the lower undercut butts 120. The parallel paths of these butts are indicated in Figure 1, the path of the lower butt having its lower edge shown as corresponding to the throat of the undercut at 122. The jacks enter the phase of operation described along either of the alternative paths P and Q. The former results from the depression of a jack under the action of cam 110. The latter results from the depression of a jack by the action of the face 114 of the cam 112. As will be evident from the drawings, the two paths differ only in that the path Q is slightly lower than the path P.

If, following the path P, one of the cams 90 engages a saw-tooth butt 119 of a jack, the butt 120 thereof will be raised sufficiently to clear the cam 96 so that the lower end of the jack will not be rocked inwardly thereby and will conse-

quently be in such position that its undercut 122 will engage the edge of the cam 84 so that it will be raised along the path R, being subsequently depressed by the action of cam 106 on its butt 118. At the top of the rise along the path R, it will serve to elevate a needle from the path A through the initial part of the path O so that the needle will be thereafter raised by the cam 18 to transfer position.

If, on the other hand, a jack following the path P is not raised by the action of a cam 90 on one of its saw-tooth butts, its butt 120 will not be raised sufficiently to clear the cam 96 with the result that the jack will be rocked inwardly and will, therefore, fail to engage the cam 84, thus following the path indicated at S. Upon reaching the cam 102, the undercut 122 of its butt 120 which will be in a radially inner position will be engaged by the cam 102 so that the lower end of the jack will be rocked outwardly for a subsequent action hereafter described (see the first jack from the left in Fig. 3).

If the jack enters the phase along the path Q, there are two possible operations which may occur. First is the normal intended one in which none of the cams 90 will engage any saw-tooth butt. Under such circumstances, the jack will not be raised from the path Q and will follow one butt position below the path S, having its lower end rocked inwardly by the cam 96 and being later picked up by the cam 102 which will slightly raise it to the indicated path S and also move outwardly its lower end. If, however, in entering along the path Q one of the saw-tooth butts is engaged by a cam 90, the jack will be raised by the cam. The rise imparted by the cam 90 is only the same as the lowering action effected by the surface 114 of the cam 112, and inasmuch as the path Q is already below the path P by the amount of this rise, the rise so resulting will not effect the missing of the cam 96 by the butt 120, in fact, leaving the jack in the same position as would occur if it entered along the path P and was not raised by a cam 90. Consequently, it will follow the path S as previously described, as if it entered along path P but was not raised by a cam 90.

The action of the cams 106 and 102 result in the paths R and S being merged before the jacks reach a position for action by the cams 92. All of the jacks are in position for engagement by the cams 92, their lower ends being positioned outwardly by reason of the action of cam 102. By the selective action of cams 92, therefore, certain of the jacks may be slightly raised to miss the cam 98 and accordingly follow the path T over the cam 88, being subsequently depressed by the cam 103. As a result of this rise, the needles are positioned as if raised by the cam 10, regardless of whether that cam is in or out, to the path F previously described. If a jack is not raised by one of the cams 92, its butt 120 will be rocked inwardly by the action of cam 98 (see the third jack in Figure 3) and, consequently, it will follow the path U, being engaged by the cam 104 having an action similar to that of cam 102, namely, positioning the lower end of the jack outwardly for another selecting action. As will be evident from Figure 1, the paths T and U merge at the position of the cam 104. Accordingly, all of the jacks are presented under the same conditions to the next selecting action by cams 94.

If a saw-tooth butt of a jack is engaged by a cam 94, the jack will be raised so that its butt

120 will clear the cam 100 and consequently it will follow the path V over the cam 88, after which it will be depressed by the cam 110 to the path P. In the rise over the cam 88, its corresponding needle will be raised so that even if the cam 12 is withdrawn, it will, by engagement with the cam 13, be brought to the path A.

If no cam 94 engages a butt of a jack, the jack will be rocked inwardly by the action of cam 100 on its butt 120 with the result that it will miss the cam 88 and will follow the path W. Upon reaching the face 114 of the cam 112, the jack will be slightly lowered and thereafter follow the path Q previously described.

15 The butts 107 of the verges 103 follow the path X which involves depressions by cams 39 and 41 respectively followed by rises over cams 43 and 45. The waves thus given to the verges correspond to the positions at which stitches are drawn by needles in the upper cylinder. The verges serve to measure the stitches by engagement of yarn between adjacent needles in the upper cylinder, their use being specially pronounced when a series of successive needles are 20 knitting in the upper cylinder and so have interposed no needles in the lower cylinder to hold the yarn downwardly.

25 It will be evident that a lower slider which has transferred its needle to an upper slider in rising over cam 18 must follow the path above cams 18, 22, 2, 30, 29, 6, 32 and 13, so as to enter the phase at A and cannot possibly get into the path B. As a result, it must be in position to receive a needle transferred from the upper cylinder at cam 62. This is of major importance since, if an empty lower slider were in path B when passing the transfer position, the corresponding upper slider would release the needle without its being received by the lower slider. Once so released, it is unlikely that the needle will be re-engaged by either slider, resulting in a load-up that will cause the needle or slider to break, or if the needle hook is contacted by a slider, the slider cannot move outwardly and breakage of 30 either the needle hook or the slider hook will occur. The invention definitely insures that no needle can ever become out of control by both sliders. If, due to some miscalculation of the pattern set-up, a lower slider fails to transfer 35 its needle to an upper slider when it should do so, no damage, except to produce an undesired pattern, will result, since the needle will remain under control of the slider though it follows an incorrect cycle.

40 The fact that the described path above the cams is necessarily followed by any lower slider which carries no needle means that so far as selection is concerned, it is possible to disregard any past performance of a slider and take into account only what is to be accomplished thereafter. Otherwise, if an empty lower slider could 45 follow one of the knitting paths, it would be necessary to insure its selection by one of the cams 94 to be sure (when cam 12 is withdrawn) that it could not enter the phase at B.

45 The foregoing is obviously of advantage to the fixer in that the pattern may be laid out in a direct fashion without keeping in mind the patterning in a preceding course. The safety race-way is necessary if there is any mixup of selection at the lap in the back of a stocking caused when the selecting cams change.

50 In the modification of Figure 5, which represents the application of the invention to a hosiery machine capable of knitting heels and toes, the

first feed is represented at 133 and may comprise a conventional series of yarn feeding fingers. Associated with this is a latch guard plate 139, the purpose of which is hereafter described.

At the main feed there are two stitch cams 140 and 142 similar in construction but adapted for alternative functioning, the upper acting upon the upper butts of the sliders in the lower cylinder during the major round-and-round knitting operations, while the lower acts upon the lower butts of such sliders during the forward reciprocations in the formation of heels and toes. A center cam 144, acting on upper butts, functions in conjunction with the cams 140 and 142 and additionally in conjunction with the reverse stitch cam 146. Guard cams 143 and 147 are provided to limit the downward movements of sliders as they are lowered by the stitch cams.

Cam 148 is provided to act upon lower butts of sliders for a purpose hereafter described. Cams 150, 152, and 154 are provided to cooperate with each other in raising sliders lowered by the forward stitch cams to provide alternative clearing of loops when in active position or the production of tuck or draw stitches by jacks when the cams are inactive. A cam 156 serves to lower sliders as hereafter described.

The second feed point is indicated at 158 and may comprise a series of yarn feeding fingers associated with cams 160 and 162 which serve to bring the needles down to draw stitches. A guard cam 164 prevents overrun of sliders in the case of stitch formation at the second feed. Cam 163 brings selected sliders to a position to present their needles for wrapping, this cam following a slider selecting means of the type indicated in Figure 1, which, however, is not indicated in this figure except by the indication of the path taken by the sliders when selection occurs. Cams 166 and 168 serve to raise sliders for purposes hereafter described.

Cam 170 serves for the raising of lower sliders to a transfer position following selection as in the modification of Figure 1 by selecting means not shown in the present modification. Cam 172 following cam 170 serves to re-lower the raised sliders which have delivered their needles to sliders in the upper cylinder. An auxiliary safety cam 171 is provided to effect the same action as cam 172 if a lower butt is broken. Cam 176 serves to raise lower sliders to a tuck level prior to the first feed point. Cam 178 serves to raise sliders as hereafter described during reverse reciprocation.

Cams 180 and 182, operating upon upper sliders, effect the transfer of needles from the upper cylinder to the lower cylinder and the return of the sliders. Cam 184 acts upon sliders during the transfer operation to free their hooks from the needle hooks. Cams 186 and 188 serve to present the needles carried by the upper cylinder to the first feed stitch cam 190, with which cooperates a guard cam 191 to avoid overrun of the upper sliders. Cams 192 and 193 serve to lower the upper sliders to effect latch clearing. Cams 194, 196, and 197 present the upper sliders to the stitch cam 198 at the second feed with which there is associated a guard cam 199 to prevent overrun of the sliders. Cams 200 and 202 following the second feed, lower the upper sliders and effect clearing of latches of the needles in the upper cylinder.

The usual raising pickers 204 and 206 blank the cams of the main feed as indicated. A lowering picker 208 normally occupies an upper inac-

tive position except when widening takes place, whereupon it is lowered into active position, the inactive position being illustrated in Figure 5.

In addition to the cams described, there are others not requiring specific mention but which act as safety cams to avoid damage in case of butt breakage, to prevent overrun of sliders, or to maintain sliders in the cylinder slots.

The sliders in the case of this modification are similar to those of Figure 1, but in this case the lower sliders are differentiated into two groups by having long and short butts, respectively. The sliders controlling instep needles are provided with short lower butts and long upper butts, while those controlling sole needles are provided with long lower butts and short upper butts so that differentiation of the two groups may be effected by partial withdrawal of cams as described below. The sliders are associated with jacks as in the modification of Figure 1.

Knitting at both feeds during rotary knitting may be accomplished in both the lower and upper cylinders. In such case, a lower slider may enter along any of the three paths A', B', or O'. In case of entry along paths O' or B', the slider will ride over cams 166 and 168 to follow the path D'. In the case of entry at A', it will also follow D', which is in the direct line of A'. After depression by center cam 144, it will then be depressed by stitch cam 140 along the path F' taking yarn at the feed station 139. Thereupon it will ride over cams 150, 152, and 154 to the latch clearing level G' passing then beneath cam 160 and stitch cam 162 to J', taking yarn at the second feed station 158. Following this, it may continue on the path B' or, alternatively, be raised at K' by the action of suitable wrap selection mechanism on its corresponding jack in the event that the needle is to be wrapped. After being raised by cam 163 to the level at which wrapping will take place, it will re-enter the phase of knitting at O'. Latch clearing by the stitches drawn at the second feed is occasioned by the cam 168, wrapping taking place at tuck level.

In the case of sliders in the upper cylinder, they enter the phase at P', pass beneath the cam 180 to transfer their needles to the cylinder sliders, then rise over cam 182 beyond which needles are transferred to upper sliders which are to control the taking of yarn. The sliders then pass over cam 186 by which they are brought to a level such that their needle latches are positioned to be held open by the latch guard plate 139. They then rise over the stitch cam 190, taking yarn at the first feed. Depression of the upper sliders then occurs under the action of cams 192 and 193, the needles being lowered by the latter to a latch clearing position. They then rise over cam 194, pass above cam 196, and then rise over stitch cam 198 taking yarn at the second feed. They are then lowered by cams 200 and 202, the latter effecting clearing of the latches and bringing them back to the path P'.

Tucking may be effected at the first feed by needles controlled in the lower cylinder if cam 166 is withdrawn, with the result that the sliders follow the path B', L' rather than path B', D' moving at the tucking level as contrasted with D' which is at the latch clearing level. The remaining path will be the same as that involved in knitting at the second feed, clearance of both stitches occurring as passage over the cam 154 takes place.

If tucking at the second feed is to occur, the

13

conditions are again similar to that involved in knitting at both feeds with the exception that cam 154 is now withdrawn and rise of the lower sliders first occurs, after the yarn is taken, by passing over cam 150 along the path H' whereby the needles are raised to a tuck level. Provision is not made in the set-up illustrated for tucking in the upper cylinder.

Draw stitches may be produced at the first feed in the lower and upper cylinders. If this is to occur at the first feed in the lower cylinder, cams 166 and 176 are both withdrawn so that the lower sliders follow the successive paths B' and M' passing below the stitch cam 140 at the first feed. Thereafter by the action of cams 150, 152, and 154, they are raised to the latch clearing level at G' and are ready to pass through the stitch drawing wave at the second feed.

In case draw stitches are to be produced in the upper cylinder at the first feed cam 200 is withdrawn, in which case, after leaving the stitch cam 198 at the second feed, the upper sliders will follow the path Q', thereby passing above the stitch cam 190.

If selective formation of draw stitches is to occur at the second feed in the case of lower cylinder needles, cam 150 is withdrawn so that the lower sliders, after leaving the stitch cam 140, will follow the path I', J', if not raised by jacks, below the stitch cam 162 thereafter following either the path K', O' or the path B' previously described, the former being followed if wrapping is to occur.

If non-selective draw stitch production is to occur in the upper cylinder at the second feed, cam 192 is withdrawn so that the upper sliders, after passing the stitch cam 190, will follow the path R' above the stitch cam 198, missing the yarn at the second feed. Thereafter these sliders are again engaged by cams 200 and 202 to follow the path P'.

As has been previously indicated, the sliders which carry instep needles are provided with short lower butts. If the cam 176 is withdrawn to miss all butts and cams 150 and 178 are partially withdrawn so as to engage long butts but miss short butts, the short butt instep sliders will reciprocate in the path made up of M', I', J' and B'. The needles carried by these sliders accordingly fail to engage any yarn at either feed, holding loops during the formation of the heel and toe for resumption of the knitting of the instep or the loopers rounds. The long lower butt sliders, on the other hand, will, in a forward reciprocation, follow substantially the normal knitting path involved in knitting yarn at the first feed. However, in this case, the stitch cam 140 is raised so that the alternative stitch cam 142 acting on lower butts comes into action and controls the wave involved in the seizure of yarn. The path in a forward reciprocation is then A', D', F', G', cams 150 and 154 raising the sliders, after knitting, to a latch clearing level.

In a reverse reciprocation, the long butt sliders will enter the phase from the left at the level of path A', will pass withdrawn cam 160, will ride over stitch cam 142, will be lowered by center cam 144 to ride down the stitch cam 146 taking yarn at the first feed, and will then ride over the cam 178 to a latch clearing level.

This action occurs for all except the picked sliders which, on each reciprocation during a narrowing operation, will be those which precede the group of long lower butt sliders. The action of the pickers is to raise the sliders to the level

14

of the path N' at which level the picked up sliders will ride past the withdrawn cams 174 and 156 in both directions of reciprocation. In the subsequent widening operation, this same picking occurs with the additional picking down of two needles upon each reciprocation in the usual fashion by the lowering picker 203 which will effect lowering of the sliders to the active levels.

With respect to avoidance of possible loss of control of a needle by both of its sliders, the action of the arrangement of Fig. 5 is similar to that of Fig. 1. A lower slider, which transfers a needle to the upper cylinder by jack selection power to cam 170 followed by a transferring rise over that cam is constrained to follow a path below cams 171 and 172 (and above the guard cam 173), above cam 144, under 174, over 148, above guard cam 149, and under 156, leaving the phase along the path A' which insures its location in position to receive any needle transferred from the upper cylinder. It cannot possibly get into the path B' which is followed by sliders controlling needles for various operations as described above. Even with an error in the set-up of the patterning controls, therefore, it is impossible for an empty lower slider to get out of needle receiving position at the transfer point.

What I claim and desire to protect by Letters Patent is:

1. A knitting machine comprising superposed needle carriers, sliders provided with butts and needles controlled by the sliders movable in said carriers, means for transferring all needles located in one carrier to the other carrier, means for thereafter transferring selected needles from the second carrier to the first carrier, means for controlling sliders in the second carrier to cause needles therein to form selectively stitches of varying types, and means for preventing sliders which have transferred needles to the first carrier from being controlled by said means for causing the formation of stitches.

2. A knitting machine comprising superposed needle carriers, sliders provided with butts and needles controlled by the sliders movable in said carriers, means for transferring all needles located in one carrier to the other carrier, means for thereafter transferring selected needles from the second carrier to the first carrier, means for controlling sliders in the second carrier to cause needles therein to form selectively stitches of varying types, and means for preventing sliders which have transferred needles to the first carrier from being controlled by said means for causing the formation of stitches, thus positioning said last named sliders to receive needles from the other carrier in a subsequent phase of knitting.

3. A knitting machine comprising superposed needle carriers, sliders provided with butts and needles controlled by the sliders movable in said carriers, means for transferring all needles located in one carrier to the other carrier, means for thereafter transferring selected needles from the second carrier to the first carrier, means for controlling sliders in the second carrier to cause needles therein to form selectively stitches of varying types, and means for preventing sliders which have transferred needles to the first carrier from being controlled by said means for causing the formation of stitches until they have again become associated with needles.

4. A knitting machine comprising superposed needle carriers, sliders provided with butts and needles controlled by the sliders movable in said

15

carriers, means for transferring all needles located in one carrier to the other carrier, means for thereafter transferring selected needles from the second carrier to the first carrier, means for controlling sliders in the second carrier to cause needles therein to form selectively stitches of varying types, and means appurtenant to each of two feeding stations for preventing sliders which have transferred needles to the first carrier from being controlled by said means for causing the formation of stitches.

5. A knitting machine comprising superposed needle carriers, sliders provided with butts and needles controlled by the sliders movable in said carriers, means for transferring all needles located in one carrier to the other carrier, means for thereafter transferring selected needles from the second carrier to the first carrier, means for controlling sliders in the second carrier to cause needles therein to form stitches, and means for presenting sliders which have transferred needles to the first carrier from being controlled by said means for causing the formation of stitches.

6. A knitting machine comprising superposed needle carriers, sliders provided with butts and needles controlled by the sliders movable in said carriers, means for transferring all needles located in one carrier to the other carrier, means for thereafter transferring selected needles from the second carrier to the first carrier, means for controlling sliders in the second carrier to cause needles therein to form stitches, and means for preventing sliders which have transferred needles to the first carrier from being controlled by said means for causing the formation of stitches, thus positioning said last named sliders to receive needles from the other carrier in a subsequent phase of knitting.

7. A knitting machine comprising superposed needle carriers, sliders provided with butts and needles controlled by the sliders movable in said carriers, means for transferring all needles located in one carrier to the other carrier, means for thereafter transferring selected needles from the second carrier to the first carrier, means for controlling sliders in the second carrier to cause needles therein to form stitches, and means for preventing sliders which have transferred needles to the first carrier from being controlled by said means for causing the formation of stitches until they have again become associated with needles.

8. A knitting machine comprising superposed needle carriers, sliders provided with butts and needles controlled by the sliders movable in said carriers, means for transferring all needles located in one carrier to the other carrier, means for thereafter transferring selected needles from the second carrier to the first carrier, means for controlling sliders in the second carrier to cause needles therein to form stitches, and means appurtenant to each of two feeding stations for preventing sliders which have transferred needles to the first carrier from being controlled by said means for causing the formation of stitches.

9. A knitting machine comprising superposed needle carriers, sliders provided with butts and needles controlled by the sliders movable in said carriers, means for transferring all needles located in one carrier to the other carrier, means for thereafter transferring selected needles from the second carrier to the first carrier, means for controlling sliders in the second carrier to cause needles therein to form selectively stitches of varying types, and means including at least one cam between the point of selective transfer and

16

the means for controlling the formation of stitches for preventing sliders which have transferred needles to the first carrier from being controlled by said means for causing the formation of stitches.

10. A knitting machine comprising superposed needle carriers, double-ended needles mounted in said carriers, sliders in both carriers arranged to control movements of said needles, means for transferring needles from sliders in one carrier to sliders in the other, means for retransferring needles from sliders in the second mentioned carrier to sliders in the first, means controlling sliders in the second carrier subsequent to the region of retransfer to cause needles controlled by them to form stitches, means controlling sliders in the first carrier subsequent to the region of retransfer to cause needles controlled by them to form stitches, said means for controlling sliders in the second carrier selectively causing them to follow alternative paths to effect the formation of different types of stitches, and means for controlling those sliders in the second carrier which have retransferred their needles so as to avoid action thereupon by the means for controlling sliders in the second carrier to form stitches.

11. A knitting machine comprising superposed needle carriers, double-ended needles mounted in said carriers, sliders in both carriers arranged to control movements of said needles, means for transferring needles from sliders in one carrier to sliders in the other, means for retransferring needles from sliders in the second mentioned carrier to sliders in the first, means controlling sliders in the second carrier subsequent to the region of retransfer to cause needles controlled by them to form stitches, means controlling sliders in the first carrier subsequent to the region of retransfer to cause needles controlled by them to form stitches, said means for controlling sliders in the second carrier selectively causing them to follow alternative paths to effect the formation of different types of stitches and leaving them in alternative positions in at least one of which they would be incapable of receiving needles in a transfer operation and, means for controlling those sliders in the second carrier which have retransferred their needles so as to avoid action thereupon by the means for controlling sliders in the second carrier to form stitches.

12. A knitting machine comprising superposed needle carriers, double-ended needles mounted in said carriers, sliders in both carriers arranged to control movements of said needles, means for transferring needles from sliders in one carrier to sliders in the other, means for retransferring needles from sliders in the second mentioned carrier to sliders in the first, means controlling sliders in the second carrier subsequent to the region of retransfer to cause needles controlled by them to form stitches, said means for controlling sliders in the second carrier selectively causing them to follow alternative paths to effect the formation of different types of stitches, and means for controlling those sliders in the second carrier which have retransferred their needles so as to avoid action thereupon by the means for controlling sliders in the second carrier to form stitches.

13. A knitting machine comprising superposed needle carriers, double-ended needles mounted in said carriers, sliders in both carriers arranged to control movements of said needles, means for

transferring needles from sliders in one carrier to sliders in the other, means for retransferring needles from sliders in the second mentioned carrier to sliders in the first, means controlling sliders in the second carrier subsequent to the region of retransfer to cause needles controlled by them to form stitches, said means for controlling sliders in the second carrier selectively causing them to follow alternative paths to effect the formation of different types of 10 stitches and leaving them in alternative positions in at least one of which they would be incapable of receiving needles in a transfer operation, and means for controlling those sliders in the second carrier which have retransferred their needles so as to avoid action thereupon by the means for controlling sliders in the second carrier to form stitches.

14. A knitting machine comprising superposed needle carriers, double-ended needles mounted in said carriers, sliders in both carriers arranged to control movements of said needles, means for transferring needles from sliders in one carrier to sliders in the other, means for retransferring needles from sliders in the second mentioned carrier to sliders in the first, means controlling sliders in the second carrier subsequent to the region of retransfer to cause needles controlled by them to form stitches, said means for controlling sliders in the second carrier leaving them in a position in which they would be incapable of receiving needles in a transfer operation, and means for controlling those sliders in the second carrier which have retransferred their needles so as to avoid action thereupon by the means for controlling sliders in the second carrier to form stitches.

15. A knitting machine comprising superposed needle carriers, double-ended needles mounted in said carriers, sliders in both carriers arranged to control movements of said needles, and a plurality of successive control phases, each of said phases including means for transferring needles from sliders in one carrier to sliders in the other, means for retransferring needles from sliders in the second mentioned carrier to sliders in the first, means controlling sliders in the second carrier subsequent to the region of retransfer to cause needles controlled by them to form stitches, said means for controlling sliders in the second carrier leaving them in a position in which they would be incapable of receiving needles in a subsequent transfer operation, and means for controlling those sliders in the second carrier which have retransferred their needles so as to avoid action thereupon by the means for controlling sliders in the second carrier to form stitches.

16. A knitting machine comprising superposed

needle carriers, double-ended needles mounted in said carriers, sliders in both carriers arranged to control movements of said needles, and a plurality of successive control phases, each of said 5 phases including means for transferring needles from sliders in one carrier to sliders in the other, means for retransferring needles from sliders in the second mentioned carrier to sliders in the first, means controlling sliders in the second carrier subsequent to the region of retransfer to cause needles controlled by them to form stitches, said means for controlling sliders in the second carrier selectively causing them to follow alternative paths to effect the formation of different types of 10 stitches and leaving them in alternative positions in at least one of which they would be incapable of receiving needles in a subsequent transfer operation, and means for controlling those sliders in the second carrier which have retransferred their needles so as to avoid action thereupon by the means for controlling sliders in the second carrier to form stitches.

17. A knitting machine comprising superposed needle carriers, double-ended needles mounted in said carriers, sliders in both carriers arranged to control movements of said needles, means for effecting transfer of needles from sliders in one carrier to companion sliders in the other, the sliders in one carrier, when their companion needles are associated with sliders in the other carrier, not being retracted by a knitting cam, and supplemental means for retracting such sliders at the knitting point so that they will not interfere with the knitting of stitches by their companion needles operating in the other carrier.

18. The method of controlling sliders in a knitting machine comprising superposed needle carriers, double-ended needles mounted therein, sliders in both carriers for controlling the needles, and means for controlling sliders to transfer needles and cause needles to form stitches, which comprises causing empty sliders of one carrier to travel past the region of formation of stitches in a special path to insure their proper location to receive needles in a transfer operation.

19. The method of controlling sliders in a knitting machine comprising superposed needle carriers, double-ended needles mounted therein, sliders in both carriers for controlling the needles, and means for controlling sliders to transfer needles and cause needles to form stitches, which comprises effecting selection of sliders to alternative positions, and causing all empty sliders of at least one of the carriers to occupy a position to receive needles at the location of transfer regardless of any previous selection of sliders.

PAUL W. BRISTOW.
